(57) **CLAIM**

The ornamental design for a precious gemstone setting, as shown and described.

DESCRIPTION

FIG. 1 is a perspective view of the precious gemstone setting of the present invention.

FIG. 2 is the elevation view of the precious gemstone setting of the present invention.

FIG. 3 is an end view of the precious gemstone setting of the present invention.

FIG. 4 is a second end view of the precious gemstone setting of the present invention.

FIG. 5 is a top view of the precious gemstone setting of the present invention; and,

FIG. 6 is a bottom view of the precious gemstone setting of the present invention.

FIGS. 1, 2, 5, and 6 are shown broken away to indicate indeterminate length, it being understood that the design is repeated uniformly as shown, throughout its length.
